(57) **CLAIM**

The ornamental design for a wheeled work machine, as shown and described.

DESCRIPTION

FIG. 1 is a front perspective view of a wheeled work machine embodying our new design;

FIG. 2 is a top plan view thereof;

FIG. 3 is a front elevational view thereof;

FIG. 4 is a left side view thereof;

FIG. 5 is a right side view thereof;

FIG. 6 is a rear elevational view thereof; and,

FIG. 7 is a bottom plan view thereof.

The broken line showing is for illustrative purposes only and forms no part of the claimed design.
